Primary Examiner — Rashida C. Walshon*(74) Attorney, Agent, or Firm* — Perkins Cole LLP(57) **CLAIM**

The ornamental design for a boot, as shown and described.

DESCRIPTION

FIG. 1 is an isometric view of a boot showing the new design.

FIG. 2 is a right-side view thereof.

FIG. 3 is a left-side view thereof.

FIG. 4 is a front view thereof.

FIG. 5 is a rear view thereof.

FIG. 6 is a top view thereof; and,

FIG. 7 is a bottom view thereof.

The broken lines in the drawings represent portions of the boot that form no part of the claim.
